CONTROL MECHANISM FOR PRESSING MACHINES

Frank R. Higley, Cleveland Heights, Ohio, assignor to The American Laundry Machinery Company, Norwood, Cincinnati, Ohio, a corporation of Ohio

Application December 6, 1937, Serial No. 178,205

8 Claims. (Cl. 192—131)

This invention relates to improvements in press control mechanism and more particularly to a pressing machine control applicable to laundry and garment presses.

5 An object of the present invention is the provision of a novel manual control for the energizing member for a power pressing machine. In this control a manual is movable from unoperated to an intermediate position for actuating the 10 power control member and from intermediate position to a full operated position to maintain the control member in power supply position. The invention provides spring means for normally returning the manual from intermediate to unoperated position and means whereby the spring means is moved to ineffective position when the press is safely closed. In one particular embodiment of my invention stop means is provided preventing movement of the manual beyond intermediate position until the press is safely closed and the spring means is carried by this stop means.

Another special feature of my invention is the embodiment of the above described novel control features in a safety two-hand control for a pressing machine.

A modified form of my invention applies the spring return of the manuals from intermediate to unoperated position in combination with a 30 four-bar linkage connected between a pair of safety manuals and a power control member in such a fashion that actuation of both safety manuals coincidentally is required to move the control member to power supply position. Other 35 novel features connected with this four-bar linkage are applicable to the control of any power machine.

Other novel features of my invention will be apparent from the accompanying drawings and 40 the specification and the essential features will be set forth in the claims.

In the drawings, Fig. 1 is an end elevation of a pressing machine equipped with my invention, wherein the control mechanism is shown diagrammatically with the press in open position; Fig. 2 is a similar view showing in full lines the press in safe closed position and in dot-dash lines the fully closed position of the press, the control mechanism being shown in corresponding position diagrammatically; Fig. 3 is a view of the control mechanism of Figs. 1 and 2 corresponding to fully closed position of the press; Fig. 4 is a detail view of the stop means of Figs. 1 and 2; Figs. 5 to 8 show a modified form of control mechanism omitting the showing of the press

which may be the same as in Figs. 1 to 4; Fig. 5 shows in full lines the control parts in unoperated position and in dot-dash lines a false operation of the parts; Fig. 6 shows the control mechanism in position corresponding to safe closed position of the press; Fig. 7 shows the parts in position corresponding to fully closed press position; while Fig. 8 is an elevational view of the four-bar linkage and valve of Figs. 5 to 7.

In the modification of Figs. 1 to 4, on a machine frame 10 is mounted a pressing bed 11. The frame also carries a pivoted lever or yoke 12 upon which is mounted a pressing head 13 adapted to coact with the bed 11 upon oscillation of yoke 12 by means of the toggle 14 and the connected fluid motor 15. A spring 16 normally biases the head toward open position. The fluid motor is of the cylinder and piston type having its piston rod connected to the toggle 14. Fluid is supplied to this motor through conduit 17 and valve casing 18. This casing houses a normally closed inlet valve 18a closed by a ball, as shown in the various figures, and a normally open outlet port 18b which may be closed by a shoulder on the valve stem 18c. This valve stem is actuated by a pin 19a on an equalizer bar 19 acting through a spring device 20. It will be understood that the equalizer bar and its pin are suitably mounted in the frame for motion toward and from valve stem 18c. Equalizer bar 19 is preferably operated by a pair of spaced safety manuals 21 pivotally mounted on the frame at 22 so as to require a hand of the operator on each manual for their coincidental operation. In the form shown, each manual is in the form of a bell crank having an arm 21a carrying a roller 21b, these rollers engaging opposite ends of bar 19. Movement of these manuals from the unoperated position of Fig. 1 to the intermediate position of Fig. 2 moves pin 19a sufficiently to close valve 40 18b and to open valve 18a provided both manuals are actuated coincidentally. Movement of the manuals beyond this point is prevented by the movable stop means 23 lying between the bell crank arms 21a. It will be understood that this 45 stop 23 is pivotally mounted on the frame 10 for vertical movement into and out of position between the arms 21a. The movement of the valves to the position of Fig. 2 supplies fluid to motor 15 and causes relative approach movement between the pressing members. However if either of the manuals is released the motor 15 will be evacuated and the press will open under the influence of spring 16. This is accomplished because on the stop 23 are mounted the flat 50 55

springs 24 adapted to engage the arms 21a in the position of Fig. 2 where springs 24 are loaded. If either of the manuals is released the associated spring 24 will return the manual to unoperated position, permitting the pin 19a to release valve stem 18c. The action of the air entering through supply pipe 25 will reseat the ball valve at 18a, thus shutting off the supply to motor 15.

When the press parts reach safe closed position, means is provided for removing stop 23 and rendering springs 24 ineffective, whereupon the manuals may be moved to fully operated position. The mechanism shown for this purpose comprises a rod 26 connected with stop 23 and carrying collars 26a and 26b adapted to engage the bracket 14a on toggle 14. Spring 27 normally biases the stop 23 to the position of Figs. 1 and 2 between the arms 21a. When the press reaches safe closed position collar 26a is engaged by bracket 14a and further movement of toggle 14 in press closing direction removes stop 23 in a downward direction so as to permit movement of manuals 21 to the position of Fig. 3. In moving from the position of Fig. 2 to that of Fig. 3, arms 21a pass over their dead-center position and engage against suitable stop means 28 on the frame. The spring device 29 yields to permit this over-center movement of arms 21a. The parts will remain in the position of Fig. 3 as long as it is desired to hold the press closed due to the pressure of the fluid supply on valve stem 18c and also because the arms 21a cannot return over center without compressing spring 29. To open the press the manuals 21 are returned to the position of Fig. 1 to evacuate motor 15 and permit spring 16 to open the press.

In the modification of Figs. 5 to 8, it will be understood that motor 15 is connected to a pressing machine constructed like that of Figs. 1 and 2 and supplied from conduit 25 through valve casing 18 and conduit 17. Here again the stop member 23 is connected with the press parts so that the stop normally lies in the position of Figs. 5 and 6 but is removed as shown in Fig. 7 when the press reaches safe closed position. Here the safety manuals are indicated at 29 and are connected by a four-bar linkage so as to actuate the pin 30 which has a yieldable connection with the valve stem 18c. In the form shown, two bars of the four-bar linkage are formed by the bell crank arms 29a connected with the manuals 29. The other two links 31 are pivotally connected at 32 to the arms 29a and are pivotally connected together at 33. The two manuals are pivotally mounted on the frame at 34. Referring to Fig. 5 it will be noted that if one manual alone is operated, the four-bar linkage will cause the roller 33a carried by the pivot connection 33 to move to one side of pin 30 so that the valves are not actuated, but if both of the manuals are moved coincidentally to the position of Fig. 6, roller 33a engages pin 30 and moves the valves in casing 18 to operated position so as to supply fluid to motor 15, causing press closure. Stop 23 at this time prevents movement of manuals 29 beyond the position of Fig. 6 and if either or both of the manuals is released, springs 24 on the stop 23 (which are loaded in Fig. 6) will return the manuals to unoperated position. However, when the press is safely closed, stop 23 is removed as previously described, permitting movement of manuals 29 to the fully operated position of Fig. 7. Here the sides of the four-bar linkage have crossed, that is to say, each part of the linkage 75 has passed dead-center to a position limited by

shoulders 35. The four-bar linkage will be held in this position by the yieldable connection between pin 30 and valve stem 18c and also by the action of the air on the ball valve 18a. The manuals may then be released and the press will remain closed. To open the press the manuals are returned to the position of Fig. 5.

What I claim is:

1. In a pressing machine having relatively movable pressing members, having power means for causing said relative movement from open position through a safe-closed position to a pressure position, and having a control member for said power means, actuating mechanism for said control member comprising two spaced manuals at least one of which has two stages of movement, said manuals during first stage movement of said one manual from unoperated to an intermediate position producing operation of said power means and relative approach movement of said pressing members, and by second stage movement of said one manual to full operated position maintaining said members in pressure position, means governed by the relative position of said pressing members for controlling movement of said one manual from intermediate to full operated position, and means carried by said last named means for moving said one manual from intermediate to unoperated position.

2. In a pressing machine having relatively movable pressing members, having power means for causing said relative movement from open position through a safe-closed position to a pressure position, and having a control member for said power means, actuating mechanisms for said control member comprising spaced safety manuals at least one of which has two stages of movement, said manuals during first stages movement of said one manual from unoperated to an intermediate position producing operation of said power means and relative approach movement of said pressing members, and by second stage of said one manual to full operated position maintaining said members in pressure position, spring means normally effective to move said one manual from intermediate to unoperated position, and means responsive to relative movement of said pressing members to safe-closed position for controlling movement of said one manual from intermediate to full operated position and for rendering said spring means ineffective to move said one manual to unoperated position.

3. In a pressing machine having relatively movable pressing members, having power means for causing relative movement of said members from open position through a safe-closed position to a pressure position, and having control means for said power means normally in power cut-off position, actuating mechanism for said control means comprising a pair of manuals spaced apart for two-hand safety operation, said manuals having two stages of operation, a first stage from unoperated to an intermediate position and a second stage from intermediate to full operated position, said manuals being operatively connected with said control means to require coincidental first stage actuation of both manuals to move said control means to power-supply position, spring means for moving said manuals from intermediate to unoperated position, stop means normally preventing second stage movement of said manuals, and means responsive to movement of said pressing members to safe-closed position for moving said stop means and said spring means to ineffective position.

4. Control mechanism for pressing machines as in claim 3, in which said spring means is carried by said stop means.
5. In a pressing machine having relatively movable pressing members, having power means for causing relative movement of said members from open position through a safe-closed position to a pressure position, and having control means for said power means normally in power 10 cut-off position, actuating mechanism for said control means comprising a pair of manuals spaced apart for two-hand safety operation, said manuals being movable each to opposite sides of a dead-center position, from a stable unoperated 15 position on one side of dead-center to a maintained operated position on the other side of dead-center, the arrangement of said manuals and said control means being such that coincidental movement of both manuals to an intermediate 20 position short of dead-center moves said control means to power-supply position, stop means normally preventing movement of said manuals beyond said intermediate position, spring means on said stop means engaging said 25 manuals to return them to unoperated position, and means for removing said stop means to ineffective position by relative movement of said pressing members to safe-closed position.
6. Control mechanism for pressing machines as in claim 5 in which said manuals are bell cranks rotatable toward each other, and said stop means normally lies between said bell cranks.
7. Control mechanism for pressing machines as in claim 5 in which said control means is a single member, and an operative connection is provided between said manuals and said single member comprising a four-bar linkage operable by said manuals and requiring coincidental operation 10 of both manuals to cause said linkage to engage and operate the said member.
8. In a pressing machine having relatively movable pressing members, having power means for causing said relative movement, and having a control member for said power means, actuating mechanism for said control member comprising a pair of manuals spaced apart for two-hand safety operation, and a four-bar linkage operatively connected between said member and said 15 manuals, the parts being so arranged as to require coincidental actuation of both manuals to cause said linkage to engage and operate said member. 20
